INVENTOR.
GILBERT NELSON.
BY HIS ATTORNEYS.

Williamson, Reiff & Williamson

UNITED STATES PATENT OFFICE.

GILBERT NELSON, OF CLEAR LAKE, WISCONSIN.

DESIGN FOR A LOLLIPOP.

Application filed March 26, 1927. Serial No. 21,362. Term of patent 7 years.

To all whom it may concern:

Be it known that I, GILBERT NELSON, a citizen of the United States, residing at Clear Lake, in the county of Polk and State of Wisconsin, have invented a new, original, and ornamental Design for Lollipop, of which the following is a specification, reference being had to the accompanying drawing, forming part thereof.

The figure is a perspective view of a lollipop constituting the design.

What I claim is:

The ornamental design for hollipop, as shown.

GILBERT NELSON.
